CONDIMENT DISPENSER

Peter J. Tarantolo, Chicago, Ill.

Application November 25, 1938, Serial No. 242,365

5 Claims. (Cl. 65—45)

My invention relates to condiment dispensers, and more particularly to combination-type of salt and pepper shakers, and my main object is to provide an article of this kind which is compact and efficient.

5 A further object of the invention is to construct the novel article only of two major parts, that it may be exceedingly simple.

10 A still further object of the invention is to design a dispensing control which is entirely external and may be quickly removed for cleaning if necessary.

15 Another object of the invention is to form the dispensing control with simple and effective actuating means.

An important object of the invention is to design the same along lines of neatness, and suitable for ornamental embellishment as the fancy may dictate.

20 With the above objects in view, and any others which may suggest themselves from the description to follow, a better understanding of the invention may be had by reference to the accompanying drawing, in which—

25 Fig. 1 is a side elevation of the novel dispenser, partly broken away;

Fig. 2 is a front elevation as seen from the right-hand side of Fig. 1;

30 Fig. 3 is an enlarged section on the line 3—3 of Fig. 1;

Fig. 4 is a section on the line 4—4 of Fig. 1;

Fig. 5 is an enlarged detail section on the line 5—5 of Fig. 1; and

Fig. 6 is a side view of a modification.

35 Various developments of the divided salt and pepper shaker have occurred from time to time in the patent art, but few if any of them have appeared on the market. Possibly complications in design and difficulties during use have been 40 the deterrent factors, and it has therefore been my intention to develop a dispenser of this type which makes for efficiency from every point of view.

In accordance with the foregoing, specific reference to the drawing indicates the dispenser at 45 10, the same being a container of cylindrical or other suitable form made of metal, plastic material, porcelain or glass. The container is formed with a semi-spherical top or dome 11 and a flat bottom 12.

The container 10 is made with a medial partition 13 to define internal compartments 14 and 15 for the different condiments, such as salt and pepper. The partition 13 reaches to the top 11, 55 and is made integrally with the same and the

balance of the container. The top has sets of perforations 16 for each compartment; and the bottom is formed with holes 17 for stoppers of cork or other suitable material for the compartments.

5 The top receives an accurately-fitted cap 19, which fully covers the top at one side but terminates a number of degrees shorter at the other side, as indicated at 19a. The cap is centered horizontally to be slidable over the top 11 with 10 a circular motion, so that it may have a limited swing to the right from the position of Fig. 1 to the extent where the bottom portion 19a of the cap meets the upper edge 10a of the container 10. The cap is pivotally disposed for the above 15 purpose by being formed with opposed inward beads 20 at the center which seat in circular cavities 21 formed in the top 11.

20 In order that the cap 19 may be swung in one or the other direction, the cap is extended downwardly in the region of the beads 20 with arms 22 which have knob-shaped continuations 23. The arms 22 have inward beads 24 which are adapted to seat in one or the other of laterally arranged cavities 25 formed in the container 10, 25 according to the position in which the cap is located. The arms 22 being of spring metal and with a gathering tendency, they will become locked by means of the disposal of the beads 24 in either of the cavities 25, so as to maintain 30 the cap 19 in the corresponding position.

25 The cap 19 is formed with two series of perforations 26 and 27, these being over the respective compartments 14 and 15 and positioned in relation to the top perforations 10 that only one or 35 the other condiment can issue when the dispenser is inverted and agitated, according to the position of the cap.

30 It will be evident from the above description that I have provided a combination condiment dispenser which is of exceeding simplicity, since 40 it is mostly cast or formed in one piece. The only additional major part is the cap 19, which may be quickly applied and sprung in place. Conversely, the cap can be quickly unsnapped 45 and placed under the hot water faucet to thoroughly clean it. Further, it makes a smooth but close fit, so as to permit no seepage of the condiments between it and the surface of the top 50 11. The cap is preferably made of stainless steel, 55 so as to be unaffected by the moisture or corrosive influence of salt. Thus, the cap may be depended upon to operate smoothly at all times. It is noted that the cap applies immediately to the exit zone of each compartment, so that there 55

is no opportunity at any time for the condiments to mix. Further, the knobs 23 may be actuated together or singly with the same effect.

The modification of Fig. 6 is along the same principle as the main embodiment, except that the cap 28 is much shorter and sector-shaped as seen from the side. Thus, this form of cap uncovers all of the perforations of one compartment and vice versa, as the handle 29 is swung, the extent of the swing necessarily being greater than in the previous instance. The modification may be made with the top 30 white over the salt compartment and black over the pepper compartment. Thus, the color of the exposed portion will be an indication of which compartment is open.

Whether in the main or modified form, the novel dispenser forms a neat and compact article which is doubly useful at the same time, since it always supplies both condiments as distinguished from the supply of only one condiment by the usual dispenser or shaker.

Further, only one dispenser is necessary to be purchased for both purposes or to be considered when the service of salt and pepper for the table is in view. Finally, it will be apparent that the novel dispenser readily lends itself to various modes of external ornamentation, style or embellishment, as the fancy or requirements may dictate.

While I have described the invention in two preferred forms, various minor changes and refinements may be made without departing from the principle of the invention, and I desire to consider all such changes and refinements as coming within the scope and spirit of the appended claims.

I claim:

1. A combination condiment dispenser comprising a container having a pair of laterally divided compartments and a domed top formed with sets of perforations for each compartment, and a cap for said top formed with like sets of perforations and pivotally movable to slide over said top in one or the other direction to alternately register corresponding sets of cap and top perforations, the cap and top being part spherical, the top having indentations on opposite sides, the cap having inward projections seating in said indentations to form a pivotal line for said movement, and means to lock the cap in either working position of its movement, said means comprising arms depending from the zone of said projections, and stop means between said arms and the wall of the container.

2. A combination condiment dispenser comprising a container having a pair of laterally divided compartments and a domed top formed with sets of perforations for each compartment, and a cap for said top formed with like sets of perforations and pivotally movable to slide over said top in one or the other direction to alternately register corresponding sets of cap and top perforations, the cap and top being part spherical, the top having indentations on opposite sides, the cap having inward projections seating in said indentations to form a pivotal line for said movement, and means to lock the cap in either working position of its movement, said means comprising arms depending from the zone of said projections, the container walls having laterally arranged pairs of indentations opposite said arms, and inward projections carried by the latter and adapted to register with either indentation, the arms being of spring material and with a tendency to seat in such indentations.

3. A combination condiment dispenser comprising a container having a pair of laterally divided compartments and a domed top formed with sets of perforations for each compartment, and a cap for said top formed with like sets of perforations and pivotally movable to slide over said top in one or the other direction to alternately register corresponding sets of cap and top perforations, the cap and top being part spherical, the top having indentations on opposite sides, the cap having inward projections seating in said indentations to form a pivotal line for said movement, and means to lock the cap in either working position of its movement, said means comprising arms depending from the zone of said projections, the container walls having laterally arranged pairs of indentations opposite said arms, and knobs extended from the region of the projections to form manual actuators.

4. A combination condiment dispenser comprising a container formed with a partition to define a pair of laterally spaced compartments, a domed top for the container and formed with a set of perforations for each compartment, a cap slidably over the dome with a pivotal movement to uncover either set of perforations, the sides of the cap being pivoted to the container, and extensions of the cap beyond the pivots for manual actuation to operate the cap.

5. The structure of claim 4, and means between the extensions and the walls of the container to lock the cap in either working position.

PETER J. TARANTOLO. 55
